ABSTRACT: A wheel drive mechanism having a drive motor which is substantially shrouded and protected by a gear train casing containing a gear train through which the motor drives the wheel. The drive motor is removable and, when so removed, does not expose the inside mechanism of the gear train casing.

WHEEL DRIVE MECHANISM

BACKGROUND OF THE INVENTION

This invention relates to wheel drive mechanisms, and more particularly to a wheel drive mechanism including a removable shrouded drive motor.

It is common practice, of course, to provide individual drive means for more than one wheel of a large vehicle. Generally, each of these drive means includes a drive motor, which may with advantage be a fluid motor, a gear train, and a gear train casing. See, for example, U.S. Pat. No. 3,246,715 (Pool et al.), U.S. Pat. No. 3,272,276 (Budzich), and U.S. Pat. No. 3,217,826 (Carter et al.). While these patents disclose devices which appear to be capable of driving a wheel of a vehicle, a study of each of them reveals certain structural drawbacks.

First of all, when the drive motor of Pool et al. or Carter et al. is removed, it appears that the internal gear train (through which the wheel is driven by the drive motor) is exposed to the atmosphere outside the gear train casing. This allows dirt, salt or other contamination to reach the gear train, resulting in substantial wear of these parts. The problem is complicated by the fact that oil may be contained within the casing to lubricate the gear train. If the oil level is sufficiently high, it may have to be drained from the casing before the motor is removed. Otherwise, the oil would run out of the opening in the casing left by the removal of the motor, resulting in oil running onto the motor and wheel or onto the floor.

Secondly, the drive motors of Pool et al. or Budzich do not appear to be protected by any vehicle structure, but rather appear to extend out into a relatively open position, where they can easily be damaged by a rock thrown up by a wheel of the vehicle, or the like.

Thirdly, in the Pool et al. and Budzich patents, the shaft of the drive motor has its rotational axis parallel to but spaced from the rotational axis of the wheel it drives. Because these axes are not aligned, an unfavorable moment or torque reaction is set up from the drive shaft of the drive motor through the gear train to the wheel.

It is an object of this invention to provide a wheel drive mechanism having a drive motor which is removable from a gear train through which it drives the wheel without exposing the gear train to atmosphere.

It is a further object of this invention to provide, while fulfilling the above object, a wheel drive mechanism having a drive motor which is well protected and shrouded.

It is a further object of this invention to provide, while fulfilling the above object, a wheel drive mechanism having a drive motor which has the rotational axis of its drive shaft aligned with the rotational axis of the wheel.

SUMMARY OF THE INVENTION

Broadly stated, the drive mechanism is for use in a vehicle having wheels and suspension members. The mechanism comprises a sealed casing supported by a suspension member of the vehicle. A gear train is, except for a sealingly exposed single rotatable member thereof which, when rotated, drives the wheel through the gear train, enclosed within the sealed casing. Further included is a drive motor and means for removably holding the drive motor relative to the suspension member and outside the casing, the drive motor having at least a portion of its body shrouded by the casing when so held, the shaft of the drive motor coupled with the single rotatable member when the drive motor is so held, whereby the single rotatable member may be rotated when the drive motor is actuated, the removal of the drive motor exposing only the single rotatable member of the gear train, and no other member thereof.

BRIEF DESCRIPTION OF THE DRAWINGS

These and other objects of the invention will become apparent from a study of the accompanying specification and drawings, in which:

FIG. 1 is a side elevation of a wheel and wheel drive mechanism showing the general mounting of the wheel drive mechanism;

FIG. 2 is a front elevation of the device of FIG. 1;

FIG. 3 is an enlarged fragmentary side elevation of the device, further showing the gear train;

FIG. 4 is a sectional view taken along the line 4-4 of FIG. 3.

DESCRIPTION OF THE PREFERRED EMBODIMENT

Referring to FIGS. 1 and 2, there is shown a suspension member 10 extending from a vehicle, and a wheel 12. Bolted to and supported by the suspension member 10 is a casing 14. This casing 14 houses a gear train 16 which is shown in detail in FIGS. 3 and 4 and will be described later. Bolted to a plate 18 is a drive motor 20 and a control box 22 therefor. The drive motor 20 may be of the well-known fluid type.

As seen in FIG. 4, the casing 14 is made up of two main parts: part 14A, which is directly bolted to the suspension member 10, and part 14B supported by suitable bearings 24, 26 and rotatable relative to the part 14A. The plate 18, with drive motor 20 and control box 22 fixed thereto, is fixed to the part 14A of casing 14 (and thus held relative to suspension member 10) by a series of bolts 28. An opening 30 is provided in the suspension member 10 to allow the control box 22 to seat therein when the plate 18 is so attached to the part 14A of casing 14.

As also seen in FIG. 4, all of the gear train 16, except the end of a single pinion gear 32, is enclosed within the casing 14. The single pinion gear 32 is rotatable relative to part 14A of casing 14. Seal 34 is provided between part 14A and pinion gear 32, and seal 36 is provided between part 14B and part 14A. The casing 14 is thus a sealed unit, and the end of the pinion gear 32 is sealingly exposed from the casing 14.

Pinion gear 32 meshes with ring gear 38, which has fixed to it and coaxial with it a gear hub 40. Gear hub 40 meshes with intermediate gear 42 which has fixed to it and coaxial with it pinion gear 44. Pinion gear 44 meshes with gear hub 46, which is actually a portion of the part 14A of the casing 14. A study of FIGS. 3 and 4 shows that rotation of the pinion gear 32 causes the gears 38, 40, 42, 44 to proceed as a group around gear hub 46. As they proceed, a pin 47 extending from pinion gear 44 into part 14B causes part 14B to rotate, the procession of the pin 47 along with the gears 38, 40, 42, 44 bearing on the part 14B to so rotate it relative to part 14A and suspension member 10. A similar set of gears, as at 38, 40, 42, 44, are provided opposite the set of gears within the casing 14.

The pinion gear 32 is internally splined, and receives the splined shaft 48 of the drive motor 20 when the plate 18 is bolted to the part 14A of the casing 14. The shaft 48 is thus coupled with the pinion gear 32, and rotation of the shaft 48 rotates the pinion gear 32 to in turn rotate part 14B of casing 14, as described above. It will be noted that, while the motor 20 is outside the casing 14, the body of the motor 20 is substantially shrouded and protected by the part 14A of casing 14. The motor 20 is further protected by plate 18. The wheel 12 bolts directly to the part 14B of casing 14 by means of studs and nuts, and is thus rotatable therewith. The pinion gear 32 and shaft 48 each have their rotational axes substantially aligned with each other and with the rotational axis of the wheel 12.

In operation, the casing may be provided with a quantity of oil therein to insure that the gear trains are properly lubricated. The motor 20 is coupled to suitable actuating means and is actuated thereby to drive the wheel 12 through the gear train 16 as described above. The motor 20, being shrouded by the casing 14, is protected from damage thereto by rocks and the like which may be thrown up by the wheel 12, and is protected from weathering also. The drive of the wheel 12 sets up no unfavorable torque reaction because the shaft 48, pinion gear 32, and wheel 12 all rotate about the same axis.

If it is desired that the motor 20 be removed, all that is necessary is the removal of the series of bolts 28. The motor

20, along with plate 18 and control box 22, may then be removed, the shaft 48 uncoupling from the pinion gear 32. None of the gear train 16 is exposed to atmosphere by such removal, meaning that no foreign matter can enter the casing 14. Furthermore, the oil within the casing 14 is not interfered with, since the casing 14 remains sealed even after the motor 20 has been removed.

Obviously, the invention can be carried out in many ways, and the embodiment shown and described is merely illustrative. Therefore, we do not wish to be limited by that embodiment, but only by the following claims. 10

We claim:

1. In a vehicle having wheels and suspension members, a mechanism for driving a wheel thereof comprising: 15
  - a. a sealed casing received within said wheel, said casing having a fixed portion supported by a suspension member of the vehicle and a portion rotatable with respect to said fixed portion supporting said wheel;
  - b. a gear train which, except for a sealingly exposed single internally splined rotatable member thereof is enclosed 20

within the sealed casing;

- c. said gear train and said rotatable portion of said casing being rotatable about said fixed portion of said casing to drive said wheel;
- d. a drive motor; and
- e. means for removably holding the drive motor relative to the suspension member and outside the casing, the drive motor having its entire body shrouded by the fixed portion of said casing when the drive motor is held relative to the suspension member, the shaft of the drive motor being externally splined to mate with said single internally splined rotatable member when the drive motor is so held, the rotational axes of said single rotatable member and drive motor shaft being each substantially aligned with the rotational axis of said wheel, whereby said single rotatable member may be rotated by said drive motor shaft when said drive motor is activated, the removal of the drive motor exposing only the single rotatable member of the gear train, and no other member thereof.
